UNITED STATES PATENT OFFICE.

EDWARD MOORE, OF COLONIE, AND SIDNEY F. WELSH, OF DELMAR, NEW YORK.

DESIGN FOR A COW-TAIL HOLDER.

54,667.

Specification for Design.

Patented Mar. 9, 1920.

Application filed September 10, 1919. Serial No. 323,021. Term of patent 14 years.

To all whom it may concern:

Be it known that we, EDWARD MOORE, a citizen of the United States, resident of Colonie, county of Albany, and State of New York, and SIDNEY F. WELSH, a citizen of the United States, resident of Delmar, county of Albany, and State of New York, have invented a new, original, and ornamental Design for Cow-Tail Holders, of which the following is a specification, reference being had

to the accompanying drawing, forming part thereof.

The single figure of the drawing is a view in perspective of a cow-tail-holder, embodying our design.

We claim:

The ornamental design for a cow-tail holder, as shown.

EDWARD MOORE.
SIDNEY F. WELSH.
